Oscar C. Schmidt, Cincinnati, Ohio, assignor to
The Cincinnati Butchers' Supply Company,
Cincinnati, Ohio, a corporation of Ohio

Application February 16, 1939, Serial No. 256,682

24 Claims. (Cl. 100—57)

My invention relates to presses for use in pressing material, and primarily in pressing bacon or the like into desired forms and sizes so as to incorporate into the body of the bacon any protruding surfaces, ragged edges or projections, to provide straight edges, right angular corners and flat sides, in order that the bacon may be cut without waste, and that the slab or side of bacon may be cut into strips of uniform size and pleasing appearance.

My invention consists in novel means for accomplishing these purposes; further, in providing a novel press box for the material; further, in providing a plurality of forms of different sizes arranged to be selectively placed in operative positions for coaction with the bacon and a coacting pressure member, the selected form and pressure member being so arranged as to have pressing movement therebetween; further, in providing novel lateral walls between which the bacon is located while being pressed and novel means for relative movement between said lateral walls for coaction with the bacon in novel manner to press the bacon edgewise in order that the slab or side of bacon shall acquire the desired size, thickness and form; further, in mounting various forms of different sizes on a movable carrier so arranged that by moving the carrier the desired form is brought into coactive position with the pressure member; further, in providing a lateral wall in conjunction with the form and novel means whereby to move the form with its lateral wall for acting compressingly on the bacon; further, in providing novel lateral walls which coact with the form to enclose the bacon in novel manner, and novel means for movement between the walls for compressing the bacon edgewise; and, further, in providing novel means for approach between the form and the coacting pressure member, between which the bacon is located, for compressing the bacon in the direction of its thickness.

My invention consists, further, in providing a novel bacon press and forms therefor of different sizes in association with which respectively sides of bacon of different sizes may be pressed, and means whereby the form for any given side of bacon may be readily placed in active relation in the press for coaction with the selected side of bacon for pressing the same, whereby uneven sides of bacon of various sizes may be respectively pressed in coaction with forms of respectively the desired sizes to reduce the sides of bacon to the most advantageous even forms and

sizes, for producing most uniform slices therefrom to enhance the value of the product.

My invention consists, further, in providing novel fluid means and controls for the same whereby the desired coactive positions between the form and the coacting pressure member and the lateral walls are obtained; and, further, in providing novel means for controlling the approach between lateral walls and between the pressure member and the form for desired controlled action upon the bacon.

The invention will be further readily understood from the following description and claims, and from the drawings, in which latter:

Fig. 1 is a front elevation of my improved device, partly broken away.

Fig. 2 is a plan view of the table and parts mounted thereon, partly broken away.

Fig. 3 is a vertical sectional detail view of the main cylinder and piston, taken on the line 3—3 of Fig. 2, and partly broken away.

Fig. 4 is an end elevation of my improved device.

Fig. 5 is a vertical cross-section of the same, taken on the irregular line 5—5 of Fig. 1.

Fig. 6 is a vertical longitudinal section of my improved device, taken on the line 6—6 of Fig. 4, and partly broken away.

Fig. 7 is a detail sectional view of the mounting of the end wall on the table, taken in the plane of the line 7—7 of Fig. 6.

Fig. 8 is a sectional detail view of the form carrier, taken on the line 8—8 of Fig. 6, and partly broken away.

Fig. 9 is a central vertical cross-section of my improved device, taken on the line 9—9 of Fig. 1, showing the table in retracted relation in full lines and in pressing relation in dotted lines, and partly broken away.

Fig. 10 is a cross-sectional view of a detail showing the latter relation.

Fig. 11 is a vertical axial sectional view, showing the operating valve mechanism of my improved device, taken on the line 11—11 of Fig. 1, and partly broken away.

Figs. 12, 13 and 14 are cross-sectional views of the same, taken respectively in the planes of the lines 12—12, 13—13 and 14—14 of Fig. 11, and partly broken away; and,

Fig. 15 is a perspective view of the revolving valve member.

In the present exemplification of my invention, (Figs. 1, 4, 5, 6 and 9), there is a frame 21 comprising a hollow base 22, having side walls 23, provided with openings 24, through which a part

of the mechanism in the base may be viewed and operated. Posts 26 are secured to the base and extend upwardly therefrom at its respective ends. The upper ends of the posts are connected by a yoke 21, having a rigid bridge 28, and depending ends 29, the lower ends of which are suitably connected with the upper ends of the posts for providing a rigid structure.

In the present exemplification cylinders 31, 32 in cylinder blocks 33, 34 are provided at the respective ends of the frame, the cylinder blocks being shown as part of the frame. Each of the cylinder blocks is provided with an upper seat 35. Feet 36 of the depending ends of the yoke are supported by these seats and are secured thereto by bolts 37. The upper end of each of the upright posts is provided with a collar 38 having a flange 39, the collar being secured to the post as by having threaded connection 40 therewith, whereby to adjust the relative heights of the flanges. The cylinder blocks are respectively provided with flanges 41. The flanges 39 and 41 are supportingly connected and rigidly secured together by bolts and nuts 42.

Plates or forms of various dimensions are provided for accommodating sides or slabs of bacon of different sizes, such forms being shown at 45, 46, 47 and 48, (Figs. 1, 4, 5, 6 and 9), respectively form pressure members, and are arranged to be brought selectively into coactive relation with a coacting pressure member 49 of the press box 50 between which the side or slab of bacon is arranged to be placed for being pressed.

These forms are preferably mounted on a form carrier 51 movable to bring any of the forms into coactive relation with the coacting pressure member 49. The form carrier is shown as a turret, which is rotatable so as to bring any of the forms into coactive position. Four of these forms are shown in the present exemplification, but it is obvious that the number of the same may be diminished or increased, a carrier of sufficient size being provided. If the carrier takes the form of a turret, the forms and their coactive mechanisms may be located in angular arrangement about the axis of the turret. In the present exemplification the turret is rotatably mounted about a rod or shaft 52, the respective ends of which also serve as pistons 53, 54 in the respective cylinders 31, 32. The turret is arranged to be indexed about the axis of the shaft and to be held endwise with relation to the shaft, and the shaft is preferably held non-rotating with relation to the cylinders.

Thus the turret is provided with bearings 55, 56, which are rotatable about the shaft, collars 57, 58 being secured to the shaft to locate the turret endwise on the shaft. An indexing lock 61 has a handle 62 and is pivoted on a pin 63 in a slot 64 in the collar 58, the lock being snugly located between the walls of the slot for holding the lock laterally rigid for rigid index position of the turret. This lock is arranged to be received in a coacting slot 65 in the turret for each of the forms thereon. When the handle 62 is depressed the locking end of this lock moves out of the slot 65 on the turret, whereupon the turret may be rotated and be locked in a new position upon registry of another slot 65 thereon with said lock, and for bringing another form thereon in coactive relation with the coacting pressure member. The shaft 52 is prevented from turning by means of a key 66 secured to the cylinder block 34, and entering a slot 67 extending lengthwise of the shaft.

The shaft 52 is movable endwise for purposes hereinafter described and has the pistons 53, 54 at its respective ends reciprocable in the cylinders 31, 32. (Figs. 1 and 6.) The cylinders are provided with heads 68, 69, suitably secured at their outer ends, and with ports 70, 71 at the outer ends of the respective cylinders. Operating fluid received through said respective ports move the pistons endwise. The outer ends of the pistons are provided with cup washers 72, 73. Stops 74, 75 are provided for limiting endwise movements of the turret for correctly positioning the same endwise with relation to its coacting pressure member. These stops are shown as bolts adjustably threaded into the respective cylinder blocks, having jam nuts 76, 77 to clamp the bolts in adjusted positions. The cylinders and pistons are an example of fluid actuated motor arranged to stall and build up back pressure in the fluid feed passage upon completion of its movement.

The coacting pressure member 49 is shown as a plate or table having a pressing face 78 and is shown on a slide 79, provided with bearings 81, at its respective ends about the posts 26, and movable up and down on said posts. A main cylinder 82 is mounted on the base 22 (Figs. 1, 2, 3, 5, 6 and 9) and is provided with an upper flange 83 fixed to the top wall 84 of the base by bolts and nuts 85, the top wall having an opening 86 through which the cylinder extends. The cylinder has an upper head 91 fixed to the upper cylinder flange 83 by bolts and nuts 92, and has a central hole 93 through which a piston rod 94 for the table extends. This piston rod is secured to the table by a suitable connection 95, the piston rod being provided with a rounded upper end 96 received in a similarly formed socket 97 in the table, and has an annular groove 98 in which the inner edges of affixing keys 99 are located, these keys being secured to the table. The cylinder head 91 is provided with a gland packing 101 for the piston rod. The other end of the cylinder is provided with a head 102 secured to an annular flange 103 at the lower end of the cylinder by bolts and nuts 104.

A piston head 107 is reciprocable in the cylinder and is releasably secured to the piston rod by nuts 108 threaded over the reduced end of the piston rod, about which there is a bearing 109 of the piston head secured between a shoulder 110 on the piston rod and said nuts. The piston head is provided with oppositely presented cup washers 111, 112, secured to the piston head by rings 113, 114, bolts 115 passing through said rings, the piston head and said washers and nuts, for securing the same together. The main cylinder is provided with ports 118, 119 at its respective ends, through which operating fluid passes for operating the piston and raising and lowering the table. The piston and cylinder are an exemplification for a fluid motor for operating the table.

Pressure walls (Figs. 1, 2, 4, 5, 6 and 9) are provided for the slab of bacon to compress the slab of bacon in its plane, that is, edgewise. These walls comprise lateral walls 121, 122, and lateral walls 123, 124 at right angles thereto. The latter walls may be termed end walls. These lateral walls have movement imparted between them for compressing the slab of bacon in the direction of its plane in the press box.

The lateral walls 121, 122 are movable toward each other along the bacon supporting face 78 of the table for pressing the side margins of the

slab of bacon toward the middle of the slab, and are retractable to normal positions. This lateral movement of these lateral walls is provided in the present instance by mounting the respective lateral walls 121, 122 on the inner end of stems 125, 126, the outer ends of the stems for the respective walls being secured to bars 127, 128. The bars are normally urged outwardly respectively by means of springs 129 located about positioning bolts 130, the bolts and springs passing loosely through holes 131 (Fig. 6) in depending walls 132 of the table, the rods passing loosely through holes 133 (Fig. 2) in the bars 127, 128, and having nuts 134, 135 received about their outer threaded ends for limiting separating movement between said bars.

Pairs of rack rods 141, 142 (Figs. 1, 2, 5 and 6) are spaced apart and operate the bars. The rack rods 141, 142 slide in bearings 143, 144 in the depending walls of the table (Fig. 5). One of the rack rods of each pair is secured in a bearing 145 in one of the bars by a pin 146 and slides in a bearing 147 in the other bar 128, and the other rack rod of each pair is secured in a bearing 148 in said other bar 128 by a pin 149 and slides in a bearing 150 in said one of said bars. These rack rods of each pair are provided with oppositely presented racks 153, 154, the teeth of which are meshed by the teeth of an intermediate pinion 155, fixed to a shaft 156, journaled in bearings 157, 158 depending from the table. The shaft is provided with spools 159 fixed to its respective ends. Each spool is arranged for receiving a flexible connection 160 thereabout. The flexible connections are shown as chains. Each of these spools is provided with a segment face 161 about which its flexible connection is wrapped. One end of each of the flexible connections is fixed to a lug 162 extending radially from the spool. The other end of each flexible connection is articulated at 163 with a rod 164. These rods are guided for longitudinal movement in bearings 165, in the flange 166 of the upper cylinder head, and pass loosely through recesses 167, 168 respectively in the upper flange 83 of the cylinder and in the upper wall 84 of the base.

Each of the rods (Figs. 5 and 6) is provided with a reduced portion 171, forming a shoulder 172 at its upper portion, against which a collar 173 abuts. A spring 174 is located about each of the reduced portions of said rods between said collar and a washer 175, positioned with relation to the rod by a nut 176 and a jam nut 177 threaded over the lower threaded end of said reduced portion of the rod to adjust the tension of the spring. The washers 173 and the springs pass freely through the recesses 168, 161, the washers 173 being arrested by the bearings 165 during continuing upward movement of the rods, thereby applying pressure to the springs, which act resistantly to inward movement of the lateral walls 121, 122 for additionally stabilizing said walls and firming their movements.

When the table is raised the lateral walls 121, 122 and the rods move freely therewith until the upper ends of the lateral walls 121, 122 are substantially on a level with the lower face 178 of the form thereabove or the end wall 123 or near to such level. When the upper ends of the lateral walls have been raised sufficiently, the collar 173 is held from further upward movement by the wall of the bearing 165, and resistance is caused to further upward movement of the rods, resulting in rotation of the shaft 156, for moving

the rack rods 141, 142 secured to the respective lateral walls 121, 122, for moving said lateral walls toward each other and toward the slab of bacon therebetween, for compressing said slab laterally in its plane and contracting the slab 5 in lateral size to the width of the form toward which the slab is being moved, so that the slab of bacon will preferably have been fully compressed laterally by the time coaction thereof with the form takes place.

The inner upper corners of said lateral walls are truncated to form beveled corners 179 (Figs. 9 and 10) for avoiding detrimental interference between said inner upper corners and the lower outer corners of the form.

During this upward movement (Figs. 9 and 10), the upper ends of the lateral walls 121, 122 are received in slots 181, 182, which are located at the respective sides of each of the forms, the lateral walls being held toward the form by the inwardly presented projections 183 on the outer walls 184 of said slots, the inwardly presented faces of said projections having outwardly slanting faces 185 at the entering ends of said slots for ready reception of said lateral walls in said slots. The upper faces of the stems 125, 126 are provided with recesses 186 for accommodating the lower ends of said outer walls 184 of said slots when in fully coacting position, and the connecting walls 187 between adjacent side 30 walls are rabbeted, as shown at 188, for accommodating the actuating bars 127, 128 with which said lateral walls 121, 122 are connected.

The end walls 124, 123 are respectively located in association with the table and with the form 35 (Figs. 6, 7 and 8), and are arranged to respectively recede to permit pressure on the slab of bacon between the table and the form. The end wall on the table is arranged to reciprocate in a slot 191 in the table and in edge slots 192 at its respective ends in the depending sides 132 of said table. The outer wall of the slot 191 is enlarged as a flange 193 for backing said end wall. The end wall is provided with rabbets 194 below the surface of the table to form a reduced portion of said end wall and shoulders 195 thereon, coacting shoulders 196 being formed at the lower ends of the edge slots 192 in said table. Springs 197 are located in said slots 192 between the shoulders 195 and 196, to resiliently hold the end plate 124 in protruding position. Pins 198 in said end plate are arranged to abut upon the table for limiting upward movement of said end plate. The end plate 124 is preferably as wide as the greatest width of slab of 55 bacon it is desired to press. The end plate 124 is arranged to contact the pressing face of the form coacting therewith at the greatest distance between the coacting pressing faces while pressing the greatest thickness of bacon it is desired to press, and to recede as said distance decreases during coaction between the pressing faces.

An end plate 123 is provided for each of the forms, and is of a width corresponding to the width of the form with which it coacts. (Figs. 65 4, 5, 6 and 8). It is arranged to move perpendicularly to the pressing face 178 of the form between the end of the form and a retaining plate 201 held to the form by shoulder bolts 202 passing through the retaining plate and 70 through slots 203 in the end plate extending perpendicularly to the pressing face of the form, coaction between said bolts and the outer side walls of the slots aiding in maintaining movement of the end walls perpendicular to said 75

pressing face. Springs 204 are located in recesses 205 in the end wall between the outer ends of said recesses and shoulders 206 in the form, to press the end wall outwardly.

Referring to Figs. 1, 4, 5, 6 and 8, it will be noted that when a plurality of forms of various sizes are located on a turret, the retaining plates for the respective end walls of the respective forms are consolidated as a single retaining plate 10 provided with radiating wings in which the slots 65 of the index of the turret are located, this plate being secured to the turret by the bolts 202. When approach between the table and the form takes place, the end wall 123 will, upon contact thereof by the pressing face of the table, recede into the form, the springs 204 causing pressure between said end wall and said pressing face during further approach between the pressing faces of the table and form. Upon endwise movement between the form and the table, the slab of bacon is moved endwise for end contact between it and the end walls 123, 124 and endwise compression between said end walls, the said end walls receding with relation to the pressure faces of the table and form upon further approach between said pressing faces for further compressing the slab of bacon in the direction of its thickness.

When the table is in retracted position, there is sufficient space between the table and the turret to permit convenient placing of the selected slab of bacon on the table and the rotation of the turret for placing the proper form to coact with said slab of bacon in coactive relation with the table. During the first part of the approaching movement of the table toward the turret, the lateral walls 121, 122 move idly with the table. As this approaching movement continues, the collars 173 strike the walls of the bearings 165 through which the rods 164 pass, for arresting said collars and applying pressure to the springs 174, which reacts on the rods 164 to cause resistance upon the outer ends of the flexible connections 160 or chains in order to rotate the shaft 156 and thereby cause approach between the lateral walls 121, 122 during the further approaching movement of the table toward the turret, producing combined inward and upward movements upon said side walls in slanting inward and approaching paths toward the turret.

These slanting movements are the same for all sizes of forms until resistance is met by contact with the form or its end wall. It is desirable that the entering edges of the side walls shall enter the receiving slots 181, 182 for all the forms regardless of which form is presented toward the table. These forms are however of various widths, the widths increasing in the order of the forms marked 45, 46, 47 and 48 respectively, which may for example be seven, eight, nine and ten inches wide. The lateral walls 121, 122 will in their approach movements toward the form arrive at said given distances apart in the order named, that is to say, it will require further approach movement toward the turret as the widths of the forms decrease for proper coaction between the lateral walls with the sides of the respective forms and proper entry of the advancing edges of said lateral walls into the slots at the respective sides of said respective forms.

In order to synchronize arrival of said lateral walls in proper relation with the forms of different widths, the distance of travel between the

table and the form is changed according to the width of the form. Thus the widest form is normally closest to the table in retracted position, the normal distance between the table and the form increasing with decrease in width of the form.

In order to provide for these various distances I mount the forms 45, 46, 47 and 48 on the turret at various distances from the axis of rotation of the turret, the widest form 48 being located at greatest distance from said axis so as to be closest to the table when the parts are in normal relations, the forms 47, 46 and 45 being at successively less distances from said axis. The shoulders 206 for the inner ends of the 15 springs 204 are at corresponding varying distances from said axis, being located upon flat sides (Figs. 6 and 8) of a flange 207 extending from the bearing 56 of the turret, these flat sides being parallel with the pressing faces of the respective forms on the turret and permitting similar springs to be employed for all the end walls 123.

A suitable fluid pump 211 is operated by an electric motor 212, secured to the base, (Figs. 1, 4 and 6), and is fed by a pipe 213, having passage connection with a fluid reservoir 214. The fluid is preferably a suitable oil and the pump is preferably a suitable hydraulic pump. A pipe 215 leads from the pump to an intake port 216 in the casing 217 of a valve 218. (See also Figs. 11, 13, 14 and 15). A pipe 219 has communication with a port 220 in the valve casing and has a check valve 221 and a manually operated valve 222 therein. A branch pipe 223 has passage 35 communication with the pipe 219 between the valve 222 and the check valve 221 and has passage communication with the port 118 in the main cylinder 82. (Fig. 3). A by-pass pipe 224 has passage communications with the valve 222 40 and with the pipe 219. The regulating valve 222 regulates the flow of fluid from the pump through the pipes 219, 224 and 223 to the upper end of the main cylinder for descent of the table, the check valve being then automatically closed. 45 When the main piston ascends, the discharge of fluid in the upper end of the main cylinder takes place through the pipe 223, the check valve which has been automatically opened and the pipe 219.

Another branch pipe 225 has passage communication with the pipe 224 and with the port 70 in the cylinder 31 at the outer side of the piston 53 therein. A pipe 226 has passage communication with the port 71 in the cylinder 32 at the outer side of the piston 54 therein and has passage communication with the port 227 in the valve casing 217. A pipe 228 has passage communication with a port 229 in the valve casing and with the port 119 in the cylinder 82. A pipe 230 has passage communication with a port 231 in the 60 valve casing and has a mouth 232 emptying into the reservoir 214.

The valve 218 includes a rotor 235 rotatable in a cap 236 of the valve casing, suitably secured to the body of the casing by bolts 237. The rotor 65 has a slide face 238 which coacts with the slide face 239 of the casing. An operating shaft 241 has a reduced end 242, which passes through a bearing 243 of the rotor and is journaled in a bearing 244 of the valve casing. The operating 70 shaft has a drive connection with the rotor for rotating the rotor with the shaft, as by providing the shaft with a polygonal portion 245, received in a correspondingly formed recess in the rotor. The cap 236 is provided with a bear- 75

ing 246 in which the shaft rotates. Said bearing comprises a gland packing 247.

An operating arm 248 is secured to said shaft for operating the latter. (Figs. 1, 4, 11 and 12). It is shown as a pluri-part arm comprising a hub portion 249 arranged to be secured to the shaft for rotating the same by providing the shaft with a polygonal portion 250 located in a correspondingly shaped hole in said hub portion, a suitable washer and a bolt 251 securing the parts in associated relations. The hub portion comprises a plate 252 rigid therewith, and has an operating handle 253 extending therefrom. The operating handle is secured to the plate by means of a bolt 254 on which the operating handle is pivoted, the operating handle being clamped between nuts 255, 256 threaded over the bolt. The inner end of the bolt acts as a pin 257 which serves as a stop for limiting angular movement of the operating arm and is arranged to be brought into contact with lugs 258, 259 on the bearing 246, thereby also limiting angular movements of the rotor of the valve. The plate is provided with an arcuate slot 260 on a curve described from the bolt 254 as a center. A bolt 261 passing through said slot and a coinciding hole in the operating handle, a nut 262 threaded thereover clamping the handle in adjusted angular positions to the plate.

The plate is provided with a socket 267, in which a plunger 268 is arranged to move. The plunger is provided with a stem 269, which extends outside the end of the socket and is provided with a pin 270 to limit outward movement of the plunger, which is urged by a spring 271 surrounding the said stem between the head 272 of the plunger and the bottom wall of the socket. When the handle is moved in one direction the plunger is arranged to strike a shelf 273 adjustable by slots 274 on the valve head, compressing the spring. Release of the handle in this position causes retraction of the operating arm a limited distance by the spring for holding the rotor of the valve in a given position with the slab of bacon under pressure.

The rotor of the valve is provided with a closed annular wall 277 and with an outer web 278 extending throughout the area of the rotor. (Figs. 11, 13, 14 and 15). It is also provided with partitions 279, 280, having a cavity 281 at one side thereof forming a port at the inner end of the rotor, and a cavity 284 at the other side thereof, there being a web 285 at the inner end of the latter cavity to form ports 286, 287 communicating with the latter cavity. The slide face 238 is on the inner ends of said partitions and said web, the partitions and the web being arranged to open and to close ports in the casing of the valve for controlling up and down movements of the table and endwise movements in opposite directions of the forms.

When it is desired to press a slab of bacon, it is placed on the table and the desired form on the turret, depending on the size and shape of the slab, is brought opposite the table by release, rotation and relocking of the turret, by manipulation of the turret lock 61 and manual rotation of the turret. The table is during such manipulation in retracted position, with the piston 107 in down position in the cylinder 82 and the port 119 thereof in communication with the port 229 in the casing of the operating valve 218, through the pipe 228. The port 229 at such valve setting is in communication with the cavity 281 in the rotor of the valve, which is in turn

in communication with the outlet port 231 in the valve casing, which communicates with the pipe 230, which empties into the reservoir. The turret is also in extreme right-hand position, against the stop 75, the cylinder 32 having communication with said outlet port 231 in the valve by means of the port 71 in said cylinder and the pipe 226. This is the normal or rest position of the parts.

After the bacon has been placed in position, 10 the operating arm is moved to the left (Fig. 1) for bringing the port 286 in the rotor (Figs. 3, 11, 13, 14 and 15) into registry with the port 229 in the casing, whereby fluid from the pump through the pipe 215 passes through the inlet port 216 15 in the valve casing, the port 287 in the rotor, the cavity 284 in the rotor and the port 286 in the rotor which registers with the port 229 in the valve casing, the fluid passing therethrough and through the pipe 228 through the port 119 in 20 the cylinder 82 for raising the piston therein. It will be noted that the valve casing and the valve rotor are viewed from opposite ends in Figs. 14 and 15. The opposite side of the piston 107 is open to the reservoir for relief of pressure on 25 that side of the piston through the port 118 in the cylinder 82, the pipe 223, the check valve 221, (Fig. 1), the pipe 219, the port 220 in the valve casing, the cavity 281 in the rotor and the outlet port 231 in the valve casing through the 30 pipe 230 into the reservoir.

The operator permits the operating handle to remain in this position until the table has been sufficiently raised for proper approach between the table and the form and by such approach 35 causing idle movement of the lateral walls and of one of the end walls with the table. Further movement in the same direction of the table causes movement of the lateral walls 121, 122 toward each other by contact of the collars 173 with 40 the bearings 165 in the cylinder head, to cause rotation of the shaft 156 and endwise movement in reverse directions of the rack rods 141, 142, and consequent lateral movements of the lateral walls, to compress the slab of bacon laterally, 45 limited by contact of said walls with the lateral faces of the form. Further approach movement between the table and the form causes entrance of said lateral walls into the side slots 181, 182 at the sides of the form. Such further approach 50 also causes recession of the end walls, the end wall 124 contacting the form, and the end wall 123 contacting the table, and being yieldable in directions perpendicular to the table and form respectively, against the resistance of the springs 55 197, 204, normally moving said end walls outwardly.

The operating arm being now moved further in the same direction toward the left, registry is caused between the port 227 in the valve casing and the port 286 in the rotor. The registry of these ports causes fluid to pass from the pump through the pipe 215, the inlet port 216 of the valve casing, the port 287, the cavity 284 and the port 286 in the rotor, the latter port registering with the port 227 in the valve casing, the port 229 having been closed by the web 285, and through the pipe 226 and the port 71 in the outer end of the right-hand cylinder 32 (Figs. 1 and 6), for moving the form and the end wall 70 123 in association therewith endwise to the left, and toward the end wall 124 on the table, for compressing the slab of bacon endwise whilst holding the same in pressed relation between the lateral walls 121, 122, and the table and form 75.

respectively. As the pistons and their rod or shaft and the turret mounted thereon are thus moved to the left, the fluid at the outside of the left-hand piston 53 exhausts through the port 70 in the outer end of the cylinder 31, the pipes 225, 224, 219, the port 220 in the casing, the cavity 281 in the rotor, and the outlet port 231 in the casing and the return pipe 230, emptying into the reservoir.

When such endwise movement between the form and the table has taken place to desired extent, limited by the stop 74, the operating handle is released by the operator and caused to automatically move to slight extent in retracting direction by means of the plunger 268 and spring 271, thereby slightly rotatively retracting the rotor of the valve and causing its port 286 to span the ports 221, 223 in the valve casing, the parts automatically remaining in this relation, for causing simultaneous pressure between the table and the form and endwise pressure between the end walls acting on the bacon, the slab of bacon being also confined between the lateral walls 121, 122, which coaction is continued for the desired period of time. As soon as the slab of bacon has been subjected to continuing pressure for the desired period of time, the operator returns the handle to initial position, returning the ports to the coactive relations for idle positions of the piston 107 in down position and the pistons 53, 54 at their right hand limits, as hereinbefore first described in describing the relations of the ports.

The operator has control of the speeds of upward and downward movements of the table and endwise movements in reverse directions of the form or turret, and the durations, relations and repetitions of such movements and the relative pressures exerted, by manipulation of the operating handle, the regulating valve 222 also controlling speed of descent of the table.

It is desirable that endwise relief movement of the form shall take place prior to separation between the form and the table, so that the slab of bacon shall be contacted only by uniformly descending parts when such separation takes place, thus avoiding interfering holding of any portion of the slab during such separation, for instance, to prevent curling of the end of the bacon contacted by the end wall 123. For accomplishing this the valve 222 is preferably a pressure relief valve of sufficient resistance to prevent flow of pressure fluid into the upper end of the main cylinder 82 until after the flow of the pressure fluid into the cylinder 31 has been substantially completed for right hand or relief movement of the form.

The pressure fluid during the return movements of the parts therefore passes first through the pipes 219, 224 and 225, being resisted by the pressure relief valve, until the piston 53 has reached its limit of movement toward the right, whereupon pressure builds up in the pipes 219, 224 and 225, until it exceeds the pressure limit of the pressure relief valve 222, after which the pressure fluid will pass through the pressure relief valve to cause descent of the piston 107 for descent of the table.

My improved device forms simple, convenient and readily controllable means for arrangement of the slab of bacon in the press, for desirable lateral, endwise and cross-sectional pressures upon the slab in desirable order and for desirable relative durations, for combined ones of such pressures, and for proper relief of such

pressures in desirable order, and convenient means for pressing slabs of bacon of various sizes for uniform consistency of texture in the slabs to produce uniform product, and to form the slabs so that uniform slices may be cut therefrom for enhancing the value of the product. 5

Changes in the parts, and in the structures and arrangements of the parts and mechanisms herein exemplified may of course be made without departing from the spirit and scope of my invention set forth in the accompanying claims. 10

I claim:

1. In a bacon press, the combination of a pair of pressure plates, means for approach between them for pressure upon the material between said plates, lateral walls between said plates, additional lateral walls between said plates extending transversely to said first-named lateral walls and having attachment with said respective pressure plates, and actuating means for lateral movement between said pressure plates to produce movement between said additional lateral walls for pressure upon the material. 15

2. In a bacon press employing a press box, 25 the combination of a pair of pressure plates, lateral walls to connect said plates, means for approach between said plates, operative connections therefrom to said lateral walls connected for sequential approach between said pressure plates and between said lateral walls for laterally closing the press box, end walls to connect said pressure plates extending transversely to said first-named lateral walls and having attachment with said respective pressure plates, and means 30 for endwise movement between said pressure plates for pressure by said end walls upon the material. 35

3. In a bacon press employing a press box, the combination of a pair of pressure plates, 40 lateral walls on one of said plates, and means for approach between said plates, a spaced operative connection therewith to said lateral walls operatively idle during the initial portion of said approach and operative for approach between 45 said lateral walls during a later portion of said approach between said plates to laterally close the press box.

4. In a bacon press employing a press box, the combination of a pair of pressure plates, 50 lateral walls on one of said plates, means for approach between said plates, a spaced operative connection therewith to said lateral walls operatively idle during the initial portion of said approach and operative for approach between 55 said lateral walls during a later portion of said approach between said plates to laterally close the press box, end walls between said plates having attachment with said respective plates, and means for lateral movement between said 60 plates for approach between said end walls.

5. In a bacon press employing a press box, the combination of opposed upper and lower pressure members of the press box, lateral walls of the press box, and means for approach in 65 one direction between said pressure members and for approach in another direction between said lateral walls for combined movements in said plurality of directions of said lateral walls for overlapping the side margins of one of said 70 pressure members to close the sides of the press box and for continuing approach between said opposed pressure members.

6. In a bacon press employing a press box, 75 the combination of opposed upper and lower pres-

sure members of the press box, lateral walls of the press box, means for approach in one direction between said pressure members and for approach in another direction between said lateral walls for combined movements in said plurality of directions of said lateral walls for overlapping the side margins of one of said pressure members to close the sides of the press box and for continuing approach between said 10 opposed pressure members, an end pressure wall resiliently mounted on each of said pressure members to coact with the pressure face of the other of said pressure members, and means for endwise movement between said pressure members for approach between said end pressure walls.

7. In a press of the character described employing a press box, the combination of opposed pressure members, opposed lateral walls, and means for approach between said opposed pressure members and for resilient approach between said lateral walls for location of one of said pressure members between said lateral walls during continuing approach movement between 25 said pressure members.

8. In a press of the character described employing a press box, the combination of opposed pressure members, opposed lateral walls, means for approach between said opposed pressure members and for resilient approach between said lateral walls for location of one of said pressure members between said lateral walls during continuing approach movement between said pressure members, opposed lateral walls at substantial right angles to said first named lateral walls, and means for approach between said second named opposed lateral walls.

9. In a press of the character described employing a press box, the combination of opposed pressure members, opposed lateral walls, means for approach between said opposed pressure members and for approach between said lateral walls for location of one of said pressure members between said lateral walls, said one of said pressure members and said lateral walls having interlocking connection between them comprising elements respectively in said one of said pressure members and lateral walls and resisting separation between said lateral walls, opposed lateral walls at substantial right angles to said first named lateral walls respectively on said opposed pressure members, and means for movement between said opposed pressure members for approach between said last-named opposed lateral walls, and said elements lengthwise shiftable during said last-named approach.

10. In a press of the character described employing a press box, the combination of a table having a pressure surface, a pressure member opposed thereto, lateral walls on said table, means for opposite movements between said lateral walls crosswise of the pressure surface of said table for coaction with said opposed pressure member, means for approach between said table and said pressure member during idle relation in said last named means, and means whereby said last named means become effective during said approach for coaction between said lateral walls and said opposed pressure member in directions slanting toward each other and toward said opposed pressure member whereby to join with and overlap said opposed pressure member to laterally close the press box.

11. In a press of the character described employing a press box, the combination of a table

having a pressure surface, a pressure member opposed thereto, lateral walls on said table, means for opposite movements between said lateral walls crosswise of the pressure surface of said table for coaction with said opposed pressure member, means for approach between said table and said pressure member during idle relation in said last-named means, means whereby said last-named means become effective during said approach for coaction between said lateral walls and said opposed pressure member in directions slanting toward each other and toward said opposed pressure member whereby to join with and overlap said opposed pressure member to laterally close the press box, said opposed pressure member provided with a resilient end wall placeable between said lateral walls during said last named movements, said table provided with a coacting end wall, and means for endwise movement between said table and said opposed pressure member for pressing movement between said end walls.

12. In a press of the character described, the combination of a table having a pressing surface, an opposed pressure member having a pressing surface, lateral pressure walls movable crosswise of said pressing surface on said table to coact in overlapping relation with the lateral margins of said opposed pressure member, means for pressure movement between said table and said opposed pressure member, end walls on said table and said opposed pressure member respectively to coact respectively with the pressure surfaces of said coacting pressure member and said table, one of said end walls located between said lateral walls during pressure relation between said table and said opposed pressure member, and means for endwise movements between said table and said coacting pressure member whereby to cause corresponding movements between said end pressure walls for pressing the bacon between said table and said coacting pressure member endwise.

13. In a press of the character described, the combination of a table having a pressing surface, an opposed pressure member having a pressing surface, lateral pressure walls movable crosswise of said pressing surface of said table to coact in overlapping relation with the lateral margins of said opposed pressure member, means for pressure movement between said table and said opposed pressure member, end walls on said table and said opposed pressure member respectively to coact respectively with the pressure surfaces of said coacting pressure member and said table, one of said end walls located between said lateral walls during pressure relation between said table and said opposed pressure member, means for endwise movements between said table and said coacting pressure member whereby to cause corresponding movements between said end pressure walls for pressing the bacon between said table and said coacting pressure member endwise, and means whereby said end pressure walls resiliently yield to approach between said table and said coacting pressure member.

14. In a press of the character described, the combination of a table having a pressure surface, coacting pressure members of various dimensions, means for coactive relation between a selected one of said coacting pressure members and said table, said coacting pressure members having pressure surfaces, lateral pressure walls on said table, means for pressure movement be-

tween said table and said selected coacting pressure member, and means for resilient pressure movement between said lateral walls to move said lateral walls inwardly during said first-named pressure movement into coaction with the lateral margins of said selected one of said coacting pressure members of different dimensions to arrest approach between said lateral walls and for movement between said lateral walls and said lateral margins of said selected coacting pressure member during continuance of said first-named pressure movement in the direction of said first-named pressure movement.

15. In a press of the character described employing a press box, the combination of coacting pressure members having pressure surfaces, means for approach between said coacting pressure members, a lateral wall movable crosswise of the pressure surface of one of said pressure members, and interlocking means extending lengthwise of the other of said pressure members between said other of said pressure members and said lateral wall having interlocking elements engageable in interlocking relation by said approach to laterally close and lock the press box.

16. In a press of the character described employing a press box, the combination of coacting pressure members having pressure surfaces, means for approach between said coacting pressure members, a lateral wall movable crosswise of the pressure surface of one of said pressure members, an end wall on the other of said pressure members projected toward the pressure surface of said one of said pressure members, interlocking means extending lengthwise of said other of said pressure members between said other of said pressure members and said lateral wall having interlocking elements engageable in interlocking relation by said approach to laterally close and lock the press box, and means for endwise movement between said pressure members for compressive movement of said end wall and endwise movement between said interlocking elements.

17. In a press of the character described employing a press box, the combination of a table having a pressure surface, a lateral wall movable thereover, an operating bar at the side of said table, a stem connecting said operating bar and said lateral wall above said pressure surface, an operating rod slidable in said table below said pressure surface and having operative connection with said operating bar to operate the latter, and operating means for said operating rod including resilient means yieldable upon excess resistance to movement of said lateral wall.

18. In a press of the character described employing a press box, the combination of a table having a pressure surface, a lateral wall movable thereover, a coacting pressure member above said table, elevating means for said table, a rockable shaft on said table, operating means connecting the latter with said lateral wall, and operating means for rocking said shaft including a resilient resistance part brought into resistance relation by elevation of said table to rock said shaft and thereby move said movable wall.

19. In a press of the character described employing a press box, the combination of a table having a pressure surface, a lateral wall movable thereover, a coacting pressure member above said table, elevating means for said table, a rockable part on said table, operating means connecting the latter with said lateral wall, and operating means for rocking said rockable part includ-

ing a flexible connection about said rockable part, a rod connected therewith, a spring to resist movement of said rod, and a part with relation to which said rod has operative movement so positioned as to resist movement of said spring to thereby rock said rockable part.

20. In a press of the character described employing a press box, the combination of a base, a table having a pressure surface, a lateral wall movable thereover, a coacting pressure member above said table, a rockable part on said table, operating means connecting the latter with said lateral wall, a flexible connection about said rockable part having attachment therewith to rock the same, a rod connected therewith having longitudinal movement with relation to said base and provided with an abutment slidable thereon and normally spaced from said base, said rod provided with a second abutment fixed thereto, a spring about said rod between said abutments, and elevating means for said table whereby to elevate said lateral wall in idle lateral relation with said table during normally spaced relation of said first-named abutment, for lateral movement of said lateral wall on said table by said spring by arrest of said first-named abutment by said base and for arrest of said lateral movement of said lateral wall by said coacting pressure member during continuing elevational movement of said table.

21. In a press of the character described employing a press box, the combination of opposed pressure members provided with pressing faces, means for approach between said members, opposed lateral walls on one of said members between which the other of said members is received upon approach between said members, means for lateral approach between said lateral walls, end walls on said respective members coacting with the pressing faces of the other of said members respectively, one of said end walls receivable between said lateral walls, and means for endwise movement between said members for compressive movement between said end walls.

22. In a bacon press employing a press box, the combination of coactive pressure members and lateral walls and end walls therebetween supported by said pressure members respectively to form the press box, a fluid motor for opposite pressure and relief movements between said pressure members, a fluid motor for opposite endwise movements between said end walls for pressure and relief movements between the latter, a source of fluid pressure supply, and fluid passages between the latter and said respective fluid motors including a pressure relief valve between said passages operated to open by back pressure on the fluid by said second-named fluid motor for fluid feed between said source of fluid pressure supply and said first-named fluid motor for relief movement between said pressure members after endwise relief movement between said end walls.

23. In a bacon press employing a press box, the combination of coactive pressure members and lateral walls and end walls therebetween supported by said pressure members respectively to form the press box, a fluid motor for opposite pressure and relief movements between said pressure members, a fluid motor for opposite endwise pressure and relief movements between said end walls, a fluid passage for connection with a source of fluid pressure supply, fluid passages communicating with said respective fluid motors, fluid passages including a by-pass pas-

sage between the latter and said first-named fluid passage, and a check valve and a pressure relief valve in said last-named fluid passages, said check valve opening toward said first-named fluid passage and said pressure, relief valve having fluid connections with said fluid passages communicating with said respective fluid motors and normally closed to said first-named fluid motor and open thereto by pressure in said second-named fluid motor to feed said second-named fluid motor and said first-named fluid motor in sequence. 5

24. In a bacon press employing a press box, the combination of coactive pressure members and lateral walls and end walls therebetween supported by said pressure members respectively to form the press box, a fluid motor for opposite

pressure and relief movements between said pressure members, a fluid motor for opposite end-wise pressure and relief movements between said end walls, a pressure fluid passage, fluid passages communicating with said respective fluid motors, a control valve between said first-named passage and said last-named passages comprising ports to selectively feed said last-named passages, an operating part for said control valve to set the same to selectively feed said last-named passages, and automatic positioning means for said operating part to place the latter in position to combinedly feed said last-named passages for pressure applying relation in both said fluid motors. 10
